W. CZARSKI

FASTENER

Filed June 27, 1923

William Czarski.
INVENTOR.

UNITED STATES PATENT OFFICE.

WILLIAM CZARSKI, OF CURRY, TERRITORY OF ALASKA.

FASTENER.

Application filed June 27, 1923. Serial No. 648,159.

To all whom it may concern:

Be it known that I, WILLIAM CZARSKI, a subject of Canada, residing at Curry, Territory of Alaska, has invented a new and useful Fastener, of which the following is a specification.

This invention relates to improvements in fasteners having double gripping ends.

The primary object of the invention is to provide a fastener for various purposes, such as connecting together all pliable materials, hanging up apparel or securing apparel on a person.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

In the drawings:—

Figure 1 is a rear elevation of the invention.

Figure 2 is a front view thereof.

Figure 3 is a similar view showing the parts in open position.

Figure 4 is a similar view of one part of the invention.

Figure 5 is a similar view of the other part.

Figure 6 is an edge elevation.

Referring to the drawings in detail, the reference numeral 1 broadly indicates one part of the invention or the supporting body thereof, and the numeral 2 the other part which is pivotally secured to the supporting body through the medium of the pivot pin 3.

The supporting body 1 is provided with enlarged ends 4 and 5 respectively while the portion 6 thereof is elongated and pivotally receives the part 2 midway its ends, as clearly shown in Figure 3 of the drawings.

The part 2 is formed somewhat in the same configuration as the supporting body, with the exception that the enlarged end 7 thereof is relatively smaller than its companion end 4 of the supporting body, but the end 8 of the part 2 is of the same size as the

ends 4 and 5 and are of the same outline. 55 The ends 4 and 7 are operatively associated while the ends 5 and 8 are adapted to function in a like manner. Formed in the end 4 there is a transverse, elongated opening 9 adapted to receive a loop element of any 60 character provided it is of sufficient size to be received therein. Arranged below the elongated opening 9, the end 4 is provided with a serrated surface 10 for operating with a like serrated surface formed on the 65 relatively small end 7 of the part 2. The serrated portion of the end 4 is cammed as shown so that a gripping association is provided between the ends 7 and 10, when they 70 are associated.

The ends 5 and 8 cooperate as above mentioned and for this purpose the end 8 is provided with the cammed surface and rising from this surface there is a pair of substantially V-shaped teeth 11 arranged in spaced relation with respect to each other and adapted to be received in cam shaped grooves 12 formed on the end 8 of the part 2. 75

From the above and the structure as shown in the drawings, it will be apparent that the fastener is provided with a pair of gripping ends which may simultaneously function to connect two articles together or one gripping end may be used singly in securing strips of sheets of material in superposed relation. 80

It is thought from the foregoing description that the advantages and novel features of my invention will be readily apparent. 85

I desire it to be understood that I may make changes in the construction and in the combination and arrangement of the several parts, provided that such changes fall within the scope of the appended claim. 95

What I claim as new is:—

A fastener of the character described comprising a body portion, enlarged ends formed thereon, a serrated cammed surface formed in one end and arranged adjacent an elongated opening, substantially V-shaped teeth formed on the opposite enlarged end, a part pivotally secured to the body portion midway its ends, and enlarged ends formed thereon and cooperating with the enlarged ends of the body portion as for the purpose specified. 100

WILLIAM CZARSKI. 105
